ATTORNEY

UNITED STATES PATENT OFFICE.

JOHN OSLIN JUSTICE, OF COLUMBUS, GEORGIA.

PISTON RING.

Application filed May 29, 1923. Serial No. 642,292.

To all whom it may concern:

Be it known that I, JOHN OSLIN JUSTICE, a citizen of the United States of America, residing at Columbus, in the county of Muscogee and State of Georgia, have invented new and useful Improvements in Piston Rings, of which the following is a specification.

The object of the invention is to provide a piston ring consisting of main and supplemental elements cooperatively related so as to provide for extension of the ring laterally to adjust itself to oversize or old or worn ring grooves so that it may obtain a firm and perfect seating or fitting engagement in the groove.

A further object is to provide an expander in connection with the ring whereby lateral movement of the piston in the cylinder is prevented which results in what is commonly known as piston slap.

With these objects in view the invention consists in a construction and combination of parts of which a preferred embodiment is illustrated without defining the limits of the invention.

Figure 1 is a side elevational view of the piston employed with the improved ring, the cylinder wall being shown in section.

Figure 2 is a vertical sectional view on an enlarged scale on the line 2—2 of Figure 1.

Figures 3 and 4 are respectively perspective views of the ring elements.

Figure 5 is a perspective view of the expander.

Figure 6 is a perspective view of the lap joint at the connecting ends of the main element of the ring.

The ring consists of the main element 1 and the supplemental element 2 both of which are split to provide for the radial expansion of the ring to contact with the cylinder wall 3, the ring being carried in the usual groove of the piston 4.

The main ring 1 is in reality the working ring, being disposed against the upper wall of the piston groove and on that side or face perpendicular with the peripheral face of the ring. On the opposite face or side, the working ring is beveled as indicated at 6 to provide an acute angle between the lower side of the ring and the peripheral face so that this side is inclined away from the bottom of the piston groove in the direction of the axis of the piston.

The supplemental ring 2 is in reality a

jamb ring and its outer periphery is normally within the outer periphery of the working ring, the jamb ring having an inclined side face 7 forming an acute angle 60 with the inner face of the jamb ring and having contact with the inclined face 6 of the working ring. The bottom face of the jamb ring is square with the peripheral face and engages the lower side wall of the piston 65 groove. Obviously radial expansion of the jamb ring will, by virtue of the contacting bevel faces 6 and 7, increase the effective width of the ring as a whole so that firm contact with the upper and lower side walls 70 of the piston grooves is effected. The outer diameter of the jamb ring being less than the corresponding diameter of the working ring, provides for considerable radial expansion of the former without contact with 75 the cylinder wall. Thus the ring as a whole may be made to seat firmly in piston grooves of varying widths which will be found as a result of wear.

The working ring is provided with a lap 80 joint and at the meeting ends is expanded laterally to substantially equal the width of both itself and the jamb ring, one extremity being formed with an offset tongue 8 overlapping the tongue extension 9 on the 85 other extremity which, however, is provided with a lateral extension 10 substantially equal to the width of the jamb ring. The tongue 8, however, is reduced in thickness by removal of a portion of the stock from the 90 inner periphery, so that this tongue may engage in a seat 11 formed in the lateral extension 10 beside the tongue 9, this seat being provided by removal of stock from the outer periphery of the terminal of the work- 95 ring.

The circumferential length of the jamb ring is reduced by the removal of a section to provide a clearance space for the offset tongue 8 and the lateral extension 10.

In order to expand the rings, an expander is provided common to both rings. This expander consists of a spring 12 formed with alternate arched and straight portions 13 and 14, the expander being in 105 the form of a split ring to provide for radial extension. Longitudinally the expander is split on a center line as indicated at 15 to provide two spaced parallel spring elements which are connected together at 110 the terminals of the expander, the longitudinal split being terminated short of the

extremities of the spring. Thus one of the parallel elements of the expander bears against the working ring and the other against the jamb ring, the former being expanded radially for firm contact with the cylinder wall and the latter radially expanded for the lateral expansion of the ring as a whole due to the cam action between the bevel faces 6 and 7 of the working and jamb rings.

Since the construction provides for the firm seating of the working ring against the upper side wall of the piston groove, the working ring may be ground at the surface to secure perfect contact with the upper wall of the groove, even though the groove be materially worn. Since the outer periphery of the jamb ring does not contact with the cylinder wall, a pocket is provided in the ring groove bounded by the lower edge of the working ring, the periphery of the jamb ring and the lower side walls of the cylinder groove, this pocket serving as an oil pocket for any excess oil from any cause and since the upper wall of the oil pocket is defined by the lower beveled edge of the working ring, this beveled edge more effectively wipes off the oil from the cylinder wall than if it were square or perpendicular with the latter.

Having described the invention, what is claimed as new and useful is:—

1. A device for the purpose indicated comprising a working ring and a jamb ring having cooperative camming surfaces, the working ring being radially expansible and having a lap joint consisting of overlapping tongues the combined width of which is equal to the width of the working ring

and the jamb ring, the jamb ring having a section removed to provide clearance space for the overlapping joint of the working ring, and a radial expander common to both rings.

2. A device for the purpose indicated comprising a working ring and a jamb ring having cooperative camming surfaces, the main ring being provided with a lap joint consisting of overlapping tongues of which one is formed in extension of the working ring and the other offset therefrom, said working ring being provided with a lateral extension, said offset tongue and lateral extension being respectively reduced in thickness on the inner periphery and outer periphery to provide a seat in the extension for the reduced portion of the offset tongue, the combined width of the tongues approximating that of the main ring and jamb ring and the latter having a section removed to provide clearance space for the lateral extension and the offset tongue.

3. A device for the purpose indicated comprising working and jamb rings of which the latter is of less radial extent than the former, said rings being provided with cooperating camming surfaces to effect relative lateral movement on radial expansion of the jamb rings, and an expander consisting of alternate arched and straight portions, the expander being split on a longitudinal center line to provide two spaced parallel spring elements bearing respectively on the inner peripheries of the working and jamb rings.

In testimony whereof he affixes his signature.

JOHN OSLIN JUSTICE.
